UNITED STATES PATENT OFFICE

2,570,363

BUCKET ELEVATOR FOR HYDROCARBON CONVERSION SYSTEMS

Stanley M. Mercier, Bexley, Ohio, assignor to The Jeffrey Manufacturing Company, a corporation of Ohio

Application October 3, 1946, Serial No. 700,928

3 Claims. (Cl. 23—288)

1

This invention relates to a bucket elevator or conveyor as well as a system involving a bucket elevator and a conveyor.

An object of the invention is to provide an improved bucket elevator for elevating two materials which differ in characteristics, such as temperatures, while maintaining the different materials separated, said materials being received along different paths, conveyed to the elevator along different or parallel paths, and discharged along different paths to flow to different units in a complete system.

A further object of the invention is to provide an improved system for handling two materials of different characteristics, such as spent and regenerated catalyst materials, which may have different temperatures.

Still another object of the invention is to provide an improved multiple path or compartment bucket elevator and in the specific form one in which there is a series of centrally located bucket compartments and two series of adjacent bucket compartments, the central compartments preferably carrying relatively high temperature regenerated catalyst material or the like, while the two outside series of compartments carry lower temperature spent catalyst material, or the like.

A further object of the invention is to provide improved chute means for feeding a conveyor or elevator particularly of the above mentioned type.

Other objects of the invention will appear hereinafter, the novel features and combinations being set forth in the appended claims.

In the accompanying drawings,

Fig. 1 is a diagrammatic elevational view showing a system or installation incorporating the features of my invention;

Fig. 2 is a side elevational view of the elevator showing a portion of the guiding and supporting superstructure, the casing insulation being omitted;

Fig. 3 is a sectional view taken on the line 3—3 of Fig. 2, with parts omitted;

Fig. 4 is a view similar to Fig. 2 of a modified form of elevator;

Fig. 4^a is an enlarged detail view taken on the line 4^a—4^a of Fig. 2, looking in the direction of the arrows;

Fig. 5 is an enlarged sectional view showing particularly the skirt which supports the head section and associated mechanism in the elevator of Fig. 4;

Fig. 6 is an elevational view of the boot or foot section of the elevation of Fig. 4, the showing also

2

generally applying to the elevator of Fig. 2 except for the supporting skirt;

Fig. 7 is an enlarged transverse sectional view taken on the line 7—7 of Fig. 9, looking in the direction of the arrows;

Fig. 8 is an enlarged transverse sectional view taken on the line 8—8 of Fig. 6 of the drawings;

Fig. 9 is an enlarged side view of the elevator casing of Fig. 2 showing also associated feed chute and observation window;

Fig. 10 is a rear elevational view of the feed chute, with the elevator casing omitted;

Fig. 11 is an enlarged sectional view of a detail taken on the line 11—11 of Fig. 10, looking in the direction of the arrows;

Fig. 12 is a sectional view taken on the line 12—12 of Fig. 11, looking in the direction of the arrows;

Fig. 13 is a sectional view through the discharge chutes taken substantially along line 13—13 of Fig. 14, looking in the direction of the arrows;

Fig. 14 is a sectional elevational view taken along the line 14—14 of Fig. 13, looking in the direction of the arrows;

Fig. 15 is an enlarged sectional elevational view showing the foot shaft and associated mechanism;

Fig. 16 is an enlarged view of the casing adjacent the foot shaft showing the shaft indicator mechanism, parts being broken away;

Fig. 17 is a somewhat schematic combination sectional and elevational view of the head section of the elevator designed particularly to show the relation of the buckets while passing over the head shaft, some of the bucket details also being illustrated;

Fig. 18 is a front elevational view of the bucket conveyor showing the buckets as they travel upwardly carrying material;

Fig. 19 is a view taken along the line 19—19 of Fig. 17, with parts omitted, showing particularly one of the buckets as it moves downwardly adjacent the discharge chute and also showing parts of the chute partitions;

Fig. 20 is a sectional view through one of the buckets taken on the line 20—20 of Fig. 17 of the drawings, showing particularly one of the bucket partitions on the inside of a bucket; and

Fig. 21 is a transverse sectional elevational view of one end of the head shaft and associated bearing and seal.

In Fig. 1 of the drawings there is illustrated somewhat diagrammatically a system or installation involving my invention in one of its aspects which also includes the particular elevator which

3
as a whole and in various constituent parts represents other aspects of my invention. The system illustrated is one involved in the process of catalytic cracking of oil or hydrocarbon. As there illustrated, there is a reactor 30 provided with inlets and outlets within which catalytic cracking takes place under the stimulating action of a catalyst, from which the spent catalyst is discharged by way of conduit or pipe 31 to a feed or loading chute designated generally 32, the structure of which forms an important feature of my invention and is described in detail hereinafter.

The spent catalyst received by the loading or feed chute 32 is divided into two paths and fed to two series of outside bucket compartments in a bucket elevator 33 by which the spent catalyst is elevated to the top of said elevator 33 and discharged over a pipe or conduit 34 to a catalyst regenerative device or kiln 35 from which the regenerated catalyst is delivered by pipe or conduit 36 to a central compartment of the loading or feed chute 32 with which it is fed to a series of centrally located compartments in the elevator or conveyer or the bucket elevator 33 by which said regenerated catalyst is also elevated while being conducted between pockets of spent catalyst, the regenerated catalyst being discharged from the top of the elevator 33 to a pipe or conduit 37 and delivered to the reactor 30.

As hereinafter described more completely, while the spent and regenerated catalyst is simultaneously elevated in the bucket elevator 33 it is maintained segregated at all times, and the regenerated catalyst which has a higher temperature than the spent catalyst is conveyed by the bucket elevator in a central series of bucket compartments, with cooler spent catalyst in bucket compartments on each side thereof, thus employing the spent catalyst somewhat in the nature of a heat insulator to protect the endless elevating chains of the elevator 33.

Fig. 2 of the drawings illustrates particularly the casing and its mounting means for the elevator 33, Figs. 4, 5 and 6 illustrating another form of elevator 133 which may be employed, it being understood that the elevators 33 and 133 are similar in construction except for such differences as are obvious or are pointed out hereinafter. Figs. 7 and 8 also show sections through the bottom portions of the elevators 33 and 133, respectively, it being understood that for all practical purposes these sections show the construction of both the elevators 33 and 133.

Each of the elevators 33 and 133 includes a generally cylindrical elongated upstanding casing or housing 38 which provides a complete enclosure for endless chain bucket elevator conveyer mechanism 39 which is shown in detail in Figs. 18 to 20, inclusive, of the drawings.

In the completed unit the exterior surface of the casing or housing 38 includes a layer of insulating material which has not been shown in the drawings. This is because of the fact that the catalytic material both in its regenerated and spent form is very hot, as a consequence of which there is a high temperature within the casing 38 when the system is in operation. Because of the temperature differences which exist within the casing 38 when it is in operation, as compared with when it is shut down and particularly in view of the fact that the casing has appreciable height, for example, in one installation it is approximately one hundred and seventy-five feet high, it is necessary to provide for

5
the free expansion and contraction of said casing 38, particularly along its length. To this end I provide novel supporting or suspending and guiding features in said casings 38 of elevators 33 and 133.

In elevator 33 this supporting or suspending mechanism is in the form of a peripheral frustoconical petticoat, skirt or flange 40 which is located near the top of said elevator and adjacent the bottom of the head section 41 of said casing or housing 38. The top of the skirt 40 is rigidly attached, as by welding, preferably around its entire periphery, to a supporting and reinforcing ring or belt 42 which in turn is rigidly attached to and forms a reinforcement of the periphery of the casing or housing 38. The bottom of the skirt 40 is provided with an integral circumferential bearing flange or ring 43 about which it is rigidly attached, as by welding, which flange or ring 43 rests upon a supporting superstructure 44 which may include a pair of spaced I-beams and interconnecting cross-beams which form a part of or are attached to a building or other independent supporting structure.

25
The entire load or weight of the casing 38, including the head section 41 of the elevator 33, is supported by the superstructure 44 through the skirt 40 and ring 42. As a consequence of this fact it is evident that the casing 38, including the head section 41, is rigidly connected to the external supporting superstructure 44 in only one horizontal plane which is the plane of connection of the skirt 40 and the ring 42, and consequently the casing 38 is free to expand without strain 30
35 under the conditions of varying temperature which occur particularly between operating and non-operating conditions. For example, if the head section 41 expands it will expand upwardly from the ring 42. If the casing 38 below the ring 42 expands it can freely expand downwardly therefrom since it is hanging free except for its connection to skirt 40 through ring 42.

40
The skirt 40 also provides for diametric expansion of the casing 38. As previously set forth, the skirt 40 is in the form of a peripheral frustoconical petticoat or flange, the small diameter end of which is attached to the ring 42 and the base or large diameter end of which rests upon the stationary I-beams of the superstructure 44. In providing for the expansion of the casing relative to the superstructure the skirt 40 functions as an upstanding load supporting moment member which connects the casing 38 with the superstructure. Because the ends of the skirt substantially follow the temperatures of those members to which they are connected through conduction, the ends will expand and/or contract according to the temperatures of those members and since the superstructure is never as hot as the casing 38 the smaller end of the skirt will expand and contract with the casing while the large end of the skirt will remain more nearly at a constant temperature.

45
In view of the height of the casing 38 it is desirable to provide guide means 45 at spaced vertical intervals to guide and brace said casing 38 against excessive lateral movement which, for example, may be caused by the wind, since in most installations these elevators are built outdoors 50 and are merely supported by open frames, of which the superstructure 44 is a part. The details of these guide means 45 are shown in Fig. 4a of the drawings and are described hereinafter in connection with the description of the modification of Fig. 4.

The head shaft 46 of elevator 33 is shown in detail in Fig. 21 of the drawings, but for the time being it is sufficient to point out that it is mounted upon a pair of spaced bearings, one of which is seen at 47, there being a bearing 47 adjacent each end of the shaft, each bearing being carried in a bearing block supported upon an I-beam or other structural member 48 of the superstructure 44.

The structure of the shaft 46 and bearing 47 preferably follows the disclosure of my application Ser. No. 570,950, filed January 1, 1945, now Patent No. 2,430,236, dated November 4, 1947. The shaft 46 is preferably covered with insulating material 49 (see Fig. 21) and preferably includes a pair of friction rings 50 which are built up of a plurality of interconnected welded rings to form friction traction wheels 51 which support and drive endless spaced-apart chains 52 (see Fig. 18). The structure of the traction wheels 51 and associated chains 52 preferably follows in general the construction disclosed and claimed in my application, Serial No. 607,115, filed July 26, 1945, which has issued as Patent No. 2,525,041.

Of particular significance in connection with this phase of the invention is the fact that the complete casing or housing 38, including the head section 41, is supported from the superstructure 44, while the bucket conveyer mechanism 39 and head shaft 46 are supported from a spaced part of the superstructure including the I-beams 48. In view of the temperature variations to which the casing head 41 is subjected it is necessary to provide for relative movement between said shaft 46 and the casing head 41 so that the side walls of the head section 41 can move in planes at right angles to the axis of head shaft 46. To provide for this and still preserve the enclosing characteristic of the casing 38 I employ a novel seal 53 which is disclosed in detail in Fig. 21 of the drawings and hereinafter fully described.

The head shaft 46 is driven from an appropriate motor and speed reducing drive mechanism 54 mounted on the I-beams 48. I also preferably provide a normally closed explosion door 55 adjacent the top of the head section 41. Said head section 41 also includes a discharge chute 56 which is provided with spaced partitions 57 (see Figs. 3 and 19) which effectively form three chutes or chute compartments, the outer two of which are connected to deliver material to the spent catalyst pipe or conduit 34, and the center or intermediate one of which is connected to deliver material to the regenerated catalyst pipe or conduit 37. A hood and vent pipe 61 is provided for the three sections of the chute 56 (see Fig. 3).

As hereinafter described in detail, the bucket elevator mechanism 39 includes three series of parallel buckets or bucket compartments, the center one of which preferably carries high temperature regenerated catalyst and the two outside ones of which carry somewhat lower temperature spent catalyst so that both the spent and regenerated catalyst is elevated simultaneously in the same casing 38 while being maintained segregated at all times and being discharged over different paths and led to different receptacles, such as reactor 30 and kiln 35, respectively. The normal temperature of the regenerated catalyst is generally higher by from twenty to thirty percent than the temperature of the spent catalyst, though they are both normally at relatively high temperatures. It is desired, however, to convey the higher temperature

5 regenerated catalyst in the buckets or bucket compartments between spent catalyst to obtain the benefit of the heat insulating effect of the spent catalyst, thereby keeping the temperature on the chains 52 to a minimum. There is also another important reason for conveying the regenerated catalyst in the bucket compartments between spent catalyst. Because the temperature differential between the spent and regenerated catalyst is relatively small, as compared with the temperature differential between the regenerated catalyst and the walls of the casing and other parts of the elevator, and because the regenerated catalyst is flanked by hot spent catalyst the regenerated catalyst will give up or lose a smaller percentage of its heat. These are important features of my invention.

Attention is now directed particularly to Figs. 4, 5 and 6 of the drawings and to certain details by which the elevator 133 differs from the elevator 33 and to certain particulars in which they are similar. Except for differences in the construction of the head section 141 of the elevator 133, as compared with the head section 41 of elevator 33 and the method of supporting the casing 38 of the two elevators 33 and 133, both elevators are of substantially similar construction. The differences in support, however, provide for one difference in the relation of parts previously described in connection with the elevator 33, in that the head shaft 46 and supported conveyer mechanism 39 in the elevator 133 is supported directly from the casing 38 through the head section 141 instead of being supported independently thereof from superstructure I-beams 48. This will be evident from the following detailed description of elevator 133.

Said elevator 133 includes a petticoat, skirt or flange 140, similar to the skirt 40 of elevator 33, with which there is an associated ring 142 and ring or flange 143, the elements 140, 142 and 143 having essentially the same relative relation as the elements 40, 42 and 43. Ring 142, however, is rigidly attached to the casing 38 of elevator 133 adjacent its bottom rather than adjacent its top, and ring 143 is supported by I-beams of superstructure 144 which are adjacent the bottom thereof rather than adjacent its top. As a consequence, the casing 38 of elevator 133 is suspended or supported by the skirt 140 from the superstructure 144, with the major portion thereof projecting above the plane of support and only the foot section or bottom thereof hanging down from said plane of support.

55 The head shaft 46 of the elevator 133 is supported through bearings 47 and associated bearing blocks which are mounted upon channels of a head framework 58 which in turn is supported on a torsion ring 59 which circumscribes the top of casing 38 and which is attached thereto by a frusto-conical petticoat, skirt or flange 60, the bottom of which is welded to the torsion ring 59 and the top of which is welded to the top of the casing 38 and to the bottom 60 of the head section 141 thereof. It is thus evident that the frame 58 as well as the head shaft 46 and bucket elevator mechanism is directly supported from the casing 38 in this form of the invention. The drive mechanism 154 for the head shaft 46 is supported by the framework 58 and is similar to the drive mechanism 54. Other features of the head section 141 follow those of head section 41 which were previously described.

65 In elevator 133 guides 45 are provided between

the head and foot sections and, of course, in this instance they are above the supporting skirt 140, while they are below the supporting skirt 40 in elevator 33. They are, however, of similar construction in each instance. Said guides are provided by forming circumferential bands or belts 62 preferably constructed of angles, which belts 62 are rigidly attached to the casing 38 by welding. It may be pointed out that the casing 38 is preferably formed of a plurality of interconnected 10 tubular sections which are bolted or welded together by top and bottom section flanges which are clearly seen in both Figs. 2 and 4 of the drawings.

At spaced intervals around the belt 62 are 15 upstanding guide bars 63 which are welded to the outwardly projecting legs of the angle belts 62 and which slidably extend into notches 64 formed in brackets or clips 65 which are mounted on channelled members 244 of the superstructure 44, 20 there preferably being guides 45 located at 90 degree intervals around the periphery of the frame 38 adjacent each of the belts 62. It is thus evident that the bars 63 are rigidly attached to the casing 38 and are free to slide upwardly and 25 downwardly in the notches 64 of the brackets 65 which are rigid with the superstructure 44. These guides 45, of course, help brace the casing 38 and prevent undesirable lateral movement or twisting thereof under atmospheric influences or under the influence of the high temperature gases within said housing 38. It is to be noted that there is a small space or clearance between the outer edges of the bars 63 and the bottoms of the 30 notches 64 of the brackets 65 that permits diametrical expansion of the casing 38.

Attention is now directed to Figs. 7, 8, 9 and 15 and to the structure of the foot shaft and its associated mechanism, which structure is applicable to both elevators 33 and 133. In the bottom of the casing 38 there is foot shaft 66 (see Figs. 7 and 8), provided with spaced wheels 67 adjacent opposite ends thereof which receive and guide the chains 52 of the elevator mechanism 39, the knuckles of said chains contacting the peripheries of the wheels 67 and the side straps thereof overlapping the wheel rims. Opposite ends of the shaft 66 are supported in roller bearings 68 which are carried in a floating framework 69. The framework 69 is mounted for free vertical or up and down movement while being restrained against all other movement, it being mounted on a pair of upstanding rods or shafts 70, there being a rod or shaft 70 adjacent each side of the casing 38, as clearly illustrated in Figs. 7 and 8 of the drawings, both said rods 70 being on one side of the shaft 66. The rods 70 are attached by appropriate plates or brackets 71 both at the top and bottom (see Figs. 7 and 9) to the frame 38.

Upper and lower guide sleeves 72 (see Figs. 7, 8 and 9) are carried by and form a part of the floating frame 69 and are adapted to receive the rods 70 and slide freely therealong, thus providing for guiding of the floating frame 69 so that the shaft 66 is always in proper position to maintain the chains 52 of the bucket elevator mechanism 39 in proper alignment with chain guides 73 which are adjustably mounted by supporting brackets on the individual sections of the casing 38. That is, the guides 73 are sectionalized with the sections of casing 38, as clearly illustrated in Fig. 9 of the drawings, and each guide 73 may be individually adjusted in right angle directions so as to align it properly to receive and guide a run of a chain 52 which is adapted to be guided 70

through substantially the entire length of the casing 38.

The details of the bearings 68 can be seen by reference to Fig. 15 of the drawings, the other bearing and associated mechanism being of substantially identical construction. Each said bearing 68 therefore includes a block, casting or shell 74 removably bolted to frame 69 and roller bearings 75 which include inner and outer races mounted on the shaft 66 and casting 74, respectively. A set screw 76 holds the outer race against rotation. A disc or plate 77 is attached by screw means 78 to the end of shaft 66 and holds the inner race of the bearing 75 in place. A thrust washer 79 is interposed between a disc 77 and a removable cover plate or cap 80 for the casting 74. Thrust washer 79 is held against rotation and can be adjusted toward and from the disc 77 by a pair of set screws that extend into recesses in the washer 79, one of which set screws is seen at 81 in Fig. 16 of the drawings.

It is to be particularly noted that the shaft 66 and the bearings 68 are entirely within the casing 38, as a consequence of which there is no need for cooling said shaft 66 since it and the bearings 68 are subject to substantially the same temperature. Furthermore, this eliminates all of the normally present intricate mechanism involved providing a seal between the shaft 66 and the casing 38 which would otherwise be necessary to retain the totally enclosing characteristic of said casing 38. Access to the bearings 68 and associated mechanism is provided by removable circular or disc-like cover plates 82, there being one such cover plate adjacent each side of the casing, or, in other words, adjacent each end of the shaft 66. These cover plates are provided on the ends of projecting drums 83 (see Figs. 6, 7, 8, and 15) which are formed near the bottom of the foot section of the elevator 33 or 133, as the case may be.

In order to indicate the position of the shaft 66 at all times and also to provide means for keeping the bearings 75 free of grit, dirt, foreign material, catalyst dust or the like and preferably simultaneously to lubricate them, I provide mechanism which is shown particularly in Figs. 15 and 16 of the drawings and which will now be described. Each bearing cover plate 82 is provided with a bracket 84 which extends into a drum 83 and is attached to the bottom of a drilled rod 85. Rod 85 extends through the top of drum 83 through a stuffing box 86 and carries an outwardly extending arm 87 which in turn carries a downwardly extending pointer arm 88 which operates with an indicating scale 89 carried on the plate 82. This pointer arm 88 at all times indicates the position of the adjacent end of the shaft 66. The rod 85 is partially drilled or bored as indicated by bore 90 and adjacent its bottom is connected by a flexible tube 91 which is preferably coiled about the rod 85 and communicates with the bore 90, said tube 91 leading through a fitting provided in a hole located centrally in plate 82 so that a fluid, such as air, flue gas, or the like, may be introduced under pressure into the bearing 68. Such fluid will create pressure within the bearing 68 and flow inwardly therethrough through a non-positive seal 92, thus acting to prevent the entry of foreign material into the bearing and to blow out any grit or abrasive material or any other foreign matter which may have worked past the seal 92.

In addition to cleaning out and maintaining the bearing 68 free of foreign substances, it is

possible to lubricate it by utilizing the flowing fluid as a carrier medium for a lubricant. To this end a graphite pot 93 is provided which is connected to the bore 90 through pipe 94 and control valve 95, the previously mentioned source of fluid pressure being derived by pipe or conduit 96 and control valve 97. A control valve 98 is interposed between valves 95 and 97 and the bore 90. If control valve 95 is closed and valves 97 and 98 open, it is evident that cleaning fluid or gas will be delivered to the bearing 68. If valve 97 is closed and valve 95 is open, lubricating material, such as graphite, oil or the like, will be delivered to the pipe leading from valve 97 and some of it may find its way into bore 90. Thereafter, when valve 95 is closed and valves 97 and 98 are both open, any such graphite or lubricating material will, of course, be carried by the flowing fluid to lubricate the bearing 68. If valve 98 is closed all access to the bore 90 is shut off.

It is thus evident that the position of the shaft 66 at each side of the elevator may be determined at all times by visual indication outside the elevator casing, that the shaft 66 and associated bearings are totally enclosed, and that they may be cleaned and lubricated or just cleaned without opening the enclosing casing 38, as a consequence of which they may be cleaned and lubricated and then maintained clean while the unit is in operation.

Attention is now directed to Figs. 9 through 14 of the drawings and to the construction of the loading or feed chute 32, it being understood that this construction is applicable to both elevators 33 and 133. A number of problems have to be considered in connection with the construction of this feed chute. First of all, since the casing or housing 38 is subject to temperature variations there is relative movement between it and said chute 32 in a substantially upright plane. In addition, the feed chute 32 is in effect three feed chutes or is a three-way or three-compartment chute, since the material is divided into three paths by said feed chute and delivered into three series of buckets or bucket compartments at the bottom of the elevator mechanism 39. In addition, individual control valves are provided for each of the separate chutes or chute compartments.

Said chute 32 includes laterally spaced and downwardly sloping side walls 99 between which is a pair of partitions 100. Adjacent their tops the partitions 100 converge, as illustrated in Fig. 10 of the drawings, and come to a point so that they split the feed pipe or conduit 31 which receives the spent catalyst from reactor 30 and thus the spent catalyst is divided between the two outside ways, troughs, chutes, or compartments 101 and 102 of the multiple way chute 32. The central compartment, trough or way 103 of said chute 32 is fed by the regenerated catalyst pipe or conduit 36 and thus the regenerated catalyst flows centrally through the feed chute 32, with spent catalyst flowing on both sides thereof to troughs 101 and 102. Troughs or compartments 101 and 102 are provided with individually operable control valves 104 and 105, respectively, which are controlled by individual operating shafts and handles 106 and 107, respectively, which project from opposite sides of the trough, as clearly illustrated in Fig. 13 of the drawings. Central trough 103 is also provided with an individually controlled valve 108 provided with an operating shaft and lever 109.

It is evident by reference to Figs. 13 and 14

of the drawings that the valves 104, 105 and 108 are swingable about horizontal axes provided by their operating shafts 106, 107 and 109, respectively, and that said valves may be respectively open and closed in variable amounts, being swingable upwardly behind stationary partition means 110 (see Fig. 14). The bottom plate 111 of the chute 32 is provided with three removable wear plates 112, one for each chute 101, 102 and 103, said wear plates being removable as a unit with the upper portion of said bottom plate 111, said bottom plate 111 being split between its ends along the split line 113, as best seen in Fig. 14 of the drawings.

The feed chute 32 also includes a vertical or upstanding frame or seal plate 114 which is rigidly attached to and forms a part of said chute 32. The lower portion of the chute ways 101, 102 and 103 is of reduced height, as compared to the upper or feed portion, as clearly illustrated in Fig. 14 of the drawings, and this lower portion projects through a frame opening 115 formed in the foot or feed section of the casing 38. This lower reduced height portion of the chute 32 is free to move upwardly and downwardly in the opening 115 which has appreciably greater height than the adjacent height of the feed chute 32, thus providing for the relative movement of the casing 38 with respect to the feed chute 32 with changing thermal conditions within casing 38.

The face of the opening 115 is provided with an upstanding seal or slide plate 116 having an opening 117 therein comparable in dimensions to the opening 115 through which the lower portion of chute 32 projects and with which it has relative up and down movement. Since the seal or slide plate 116 is fixed to and moves with the casing 38 and the frame or seal plate 114 is fixed to the chute 32 it is obvious that they will have relative sliding movement in an upright or vertical plane as the casing 38 expands and contracts and thus moves rectilinearly upwardly and downwardly with respect to chute 32.

To effectuate a seal for all relative positions of plates 114 and 116, the plate 114 is provided along opposite sides with upper and lower guide brackets 118 (see Fig. 11) which are provided on their insides with notches 119 which receive interlocking outer edges of the plate 116. In addition, a spring-pressed packing 120 is carried in a groove around the periphery of the seal plate 114 and is pressed against the seal plate 116, thus insuring an effective seal between the casing 38 and the feed chute 32 for all relative positions thereof.

In addition, to prevent abrasive material accumulating between the two plates 114 and 116 which might cause damage to the seal 120 or cause undue wear on either of them, blowout pipe 121, which may be supplied with flue gas or other fluid or gas under pressure, communicates through spaced branch pipes 122 (see Fig. 12) to a transverse groove or conduit 123 formed adjacent the bottom of the plate 114 and above the bottom part of seal 120. By introducing fluid, such as air, flue gas and the like into the groove 123, abrasive material, such as catalyst dust, may be blown upwardly from the space between said plates 114 and 116.

As best seen by reference to Fig. 13 of the drawings, the lower portions of the compartments or individual chutes 101, 102 and 103 are provided with supplementary converging wall

plates 124. The function of these converging wall plates 124 is progressively to decrease the effective width of the chutes or compartments 101, 102 and 103 so that as the material flows through them and discharges from their lower edges there will be an appreciable space between the flowing material of each trough. Consequently the material in each trough or way 101, 102 and 103 will be effectively segregated without appreciable intermingling and will be separately received in individual buckets or bucket compartments of each vertical series of elevator conveyor mechanism 39, as above mentioned and as hereinafter explained in more detail.

Also, to assist in the loading of the buckets, there is a loading plate 125 (see Figs. 7 and 14) located adjacent the discharge edge of the feed chute 32 which is essentially stationary with respect to casing 38 and is provided with three laterally spaced elongated windows or openings 126, one for each of the ways or compartments 101, 102 and 103. The upper end of the loading plate 125 is rigidly connected to a bracket on the lower section of casing 38 (see Fig. 14), and the bottom is provided with a pair of pins 127 (see Fig. 9) which extend through holes in brackets 128 attached to the bottom of the lower casing section 38, there being one adjacent each side. Since there may be some difference in thermal expansion of the loading plate 125 and the casing 38 to which it is attached, the pins 127 compensate for this by being readily slideable in the holes in brackets 128, while at the same time the loading plate 125 is held essentially rigid with the lower section of casing 38.

Directly above the feed chute 32 is an observation window 129. This window 129 makes it possible for an operator to view the material within the buckets of the elevator mechanism 39 without disturbing the enclosing character of the casing 38. It has heretofore been used by me in connection with earlier elevators and therefore will not be described except briefly. In addition to the observation housing there is provided a window frame 130 which is slideable with respect to a stationary frame of the observation housing. The top portion of this window frame 130 is opaque, while the bottom portion is provided with a pair of adjacent transparent glass panels, one above the other. One of these glass panels has a lamp 131 positioned so as to direct light through it to the interior of the casing 38 so as to illuminate the bucket elevator mechanism 39. Below lamp 131 is a second window through which an observer may look to see the interior of the lighted casing 38. By sliding the frame 130 downwardly from the position illustrated in Fig. 9 of the drawings the two glass panels are directly exposed and may be readily cleaned, after which they may be returned to their operating position by sliding the frame 130 upwardly.

Attention is now directed particularly to Figs. 17 to 20 of the drawings and to certain structural features of the bucket elevator mechanism 39. Extending between and rigidly attached at opposite sides to the previously mentioned elevator chains 52 is a series of overlapping multiple compartment buckets 132 which are preferably in substantially overlapping relation, as clearly illustrated in Fig. 17 of the drawings. Each of the buckets 132 is provided with three cells, compartments or sections 134, 135 and 136. Viewed in a slightly different manner, the compartments 134, 135 and 136 may be considered as separate

buckets integrally formed to form a unit of three buckets.

It is evident that the buckets or cells 134 of a complete series along the longitudinal length of the chains 52 form one working series adapted to receive one type of material, maintaining it separate from the other buckets or compartments and discharging it along any particular chute path of the discharge chute 56. The same is true of the series of buckets or cells 135 and the series of buckets or cells 136. In other words, in the particular installation here involved, chute trough 101 delivers spent catalyst to the series of compartments or buckets 136, chute compartment 103 delivers regenerated catalyst to buckets, cells or compartments 135, and chute compartment 102 delivers spent catalyst to buckets or compartments 134, all at the bottom of the elevator. The materials thus segregated in the buckets of elevator mechanism 39 will be maintained in this relation and individually discharged to the three compartments of the discharge chute 56 adjacent the elevator top, the spent catalyst being delivered from both streams to conduit 34 and kiln 35, while the regenerated catalyst is delivered to the conduit 37 and reactor 30.

The separate compartments of the multiple buckets 132 are formed by partitions 137 which are best illustrated in Fig. 20 of the drawings. These partitions 137 are bifurcated at their outer ends, as clearly illustrated in Fig. 20 of the drawings, and, as illustrated in Figs. 17 and 18 of the drawings, the outer bifurcated end of each partition 137 overlaps or receives between its spaced parts an aligned guide fin, partition or plate 138 on the front of the preceding bucket so that cooperation between a partition 137 and fin, partition or plate 138 produces a partition which is continuous at least over some portion, particularly as each bucket 132 reaches its final discharging position, the discharging position being reached as the buckets 132 travel over the head shaft 46 which is the position of the buckets to the left of a vertical plane through shaft 46, as viewed in Fig. 17 of the drawings.

It is evident that the buckets 132 or the compartments of the multiple buckets will start to discharge as soon as a bucket passes over a point directly above shaft 46. As these buckets travel in a path which is along an arc of a circle their discharging characteristic progressively increases until they start moving rectilinearly downwardly which is the position of the lower left-hand bucket 132, as viewed in Fig. 17 of the drawings. While the buckets are moving along the arc of a circle the partitions 137 do not overlap the fins 138. However, they are in alignment with them and due to the flaring or diverging character of partitions 137, as material travels adjacent them outwardly from the buckets 132, it is evident that they will guide material in converging paths and direct the material into the guiding paths provided by the fins 138 on the front of the buckets 132, which fronts under these circumstances act as complementary feed chutes to aid in delivering and guiding the material to the stationary feed chute 56, also confining the segregated spent and regenerated catalyst to preselected paths of travel. End flanges 161 on opposite ends of buckets 132 co-operate to provide the outside complementary feed chutes on the fronts of said buckets 132.

Attention is now directed particularly to Fig. 21

of the drawings and to the construction of the traction wheel 51 and associated mechanism and the seal 53. Near opposite ends the shaft 46 is provided with the traction wheels 51 which are formed of a plurality of welded rings, as disclosed and claimed in my application, Serial No. 607,115, except for certain minor differences. These concentric rings are preferably under tension at normal temperatures so that when they expand under high temperatures they still frictionally engage each other. In addition, they are welded together adjacent their peripheral edges. The major portion of the shaft 46 is imbedded in insulating material 49 which is built up around the traction wheel 51 except for a portion of the outer ring and the friction ring or tire 50 thereof.

The outer ends of shaft 46 are supported in bearings 47 and they are cooled, as disclosed and claimed in my application, Serial No. 500,799, filed September 1, 1943, now Patent No. 2,491,899, dated December 20, 1949. The shaft 46 extends through oppositely positioned openings 139 in the head section 41 of casing 38 to reach the separately housed bearings 47, and the totally enclosed character of the casing 38 is preserved by the shaft seals 53 which provide not only for rotation of shaft 46 but also movement thereof in a plane at right angles to its axis with respect to head section 41 of said casing 38.

The seal 53 includes casting or manifold 145 in the form of a ring which surrounds or circumscribes the shaft 46 and which at its inner end is provided with a stuffing box 146 including packing rings which co-operate with a steel sleeve 147 directly attached to the shaft 46 and in effect providing a renewable packing surface thereof which co-operates with the relatively stationary stuffing box 146. Adjacent the interior edge of the casting 145 which is adjacent the sleeve 147 there is a manifold ring 148 which is attached to the manifold or casting 145 and the interior circular edge of which is spaced slightly from the sleeve 147.

A conduit 149 is provided in the casting 145 and leads to the circumferential chamber 150 formed between the manifold ring 148 and said casting 145. Air, flue gas or other fluid may be introduced through conduit 149 into the chamber 150 which will flow inwardly into the casing 38 through the peripheral orifice formed adjacent the sleeve 147, thus removing and/or preventing the entry of grit, catalyst dust, or other foreign matter into the stuffing box 146, thereby preventing undue wearing of the sleeve 147 and the packing rings of the stuffing box 146. Sleeve 147 is of such length as to provide for expansion or contraction of shaft 46 relative to casing head 47 since it can slide axially relative to packing 146. This also provides for diametrical expansion and contraction of head section 41.

Adjacent its outer periphery the casting 145 is provided with a peripheral groove which receives an adjustable seal ring 151 which has contact in a vertical plane with a seat or seal ring 152 which is rigidly but removably attached to a ring-like plate 153 which effectively forms a part of the head section 41 of the casing 38, since it is welded thereto by a ring 155. Insulating material is preferably provided on the interior of ring 155 between the main plate of head section 41 and the above-mentioned plate 153 and extends to a frusto-conical plate 156 which defines the opening 139 and forms one supporting plate for the above-mentioned insulation.

The seat or seal ring 152 is clamped rigidly to

the plate 153 and compresses a gasket against the plate 153, thus providing a removable but tight connection between said ring 152 and said plate 153. The clamping of these two members is effected by two half clamping rings 158 which are clamped by co-operating nuts and bolts 159. A clamp ring 160 also mounted on nuts and bolts 159 clamps the casting 145 to the seal ring 152, with the previously mentioned seals 151 interposed, thus providing for relative sliding movement in an upright or vertical plane between the casting 145 and the seat or seal ring 152, thus allowing for the relative movement of the head section 41 of casing 38 in an upright plane or at right angles to the axis of shaft 46.

To review briefly the operation of the system as well as the elevator 33 or 133, starting with the feeding of the spent and regenerated catalyst to the elevator, the spent catalyst flows through the feed chute 32 in the two opposite troughs or streams provided by converging troughs 101 and 102. The higher temperature regenerated catalyst is fed intermediate the streams of spent catalyst by way of trough 103 of chute 32. The feeding of these materials is controlled through each trough by its individual control valve 104, 105, 108, as the case may be.

The spent and regenerated catalyst in the three streams or troughs is directed through the loading plate 125 into three series of buckets or three series of compartments to a multiple bucket at the foot of the elevator, with the regenerated catalyst in the central series of buckets or compartments 135 and the spent catalyst in the two outside series of buckets or compartments 134 and 136. The spent and regenerated catalyst is then elevated together along the working or elevating run of the elevator which is the right-hand run, as viewed in Figs. 1, 4 and 17 of the drawings.

It is to be particularly noted that this hot material is completely enclosed by the housing 38 of the elevator 33 or 133. The complete absence of projections of the foot shaft 66 through the casing 38 simplifies this total enclosure, and effective seals 53 are provided to allow the head shaft 46 to project through said casing 38.

As the buckets pass over head shaft 46 and begin their downward travel they progressively reach a full discharging position and co-operate with each other to discharge the material while maintaining it segregated and discharging it into three streams in the discharge chute 56, the partitions 57 of which are in alignment with the partitions 137 of the buckets and with the guide partitions or fins 138 on the fronts of the buckets, all of which co-operate to maintain the segregation of the different characteristic materials, such as the spent and regenerated catalyst.

The spent catalyst is then conducted by conduit 34 from the discharge chute 56 to the kiln 35 where it is regenerated and the regenerated catalyst is delivered to conduit 31 and by it to the reactor 30 where it is employed to aid in the cracking action of the oil or hydrocarbon being treated. Spent catalyst from the reactor 30 is then delivered to feed chute 32 where it is segregated, as above described, and regenerated catalyst is delivered by conduit 36 from the kiln 35 to feed chute 32 where it is delivered to the central path or trough 103, as also above described.

As previously mentioned, the casing 38 is made up of a plurality of vertically superposed and attached sections removably connected together by top and bottom flanges and is preferably pro-

vided with insulating material on its external surface. In the form of the elevator illustrated in Fig. 2, the major portion of the casing 38 is suspended and hangs downwardly from its single support adjacent the belt 42 near its top. It is guided at spaced intervals and held against lateral swinging by the guide means 45 which provide for its free expansion and contraction.

In the elevator 133 of Fig. 4 the single support is adjacent its bottom at the belt 142, the major portion thereof extending upwardly and being similarly guided by guides 45. As also previously mentioned, in the elevator 33 of Fig. 2 the bucket elevating mechanism 39 is supported from head shaft 46 by superstructure 48 independently of the supporting of casing 38, while in the form of the elevator 133 of Fig. 4, bucket elevator mechanism 39 is supported directly from the casing 38, since the head shaft supporting framework 58 is supported through the skirt 69 from the casing 38. Except for these differences the two elevators 33 and 133 are of similar construction. This applies particularly to the bucket elevator mechanism 39 which is the same in both cases as well as the feed chutes 32, observation windows 129, discharge chutes 56, guides 45, seals 53, and foot shaft 66 and all associated mechanism described particularly in Figs. 15 and 16 of the drawings.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In an apparatus for conversion of fluid hydrocarbons in the presence of a moving contact material the apparatus which comprises in combination: means defining a conversion chamber adapted to confine a contact material, means to admit a reactant thereinto, means defining a separate contact material regeneration chamber, a substantially vertical elevator casing having a head portion and a foot portion, an endless series of articulated buckets in said casing, means to support said buckets and to move them in a closed path forming a loop in both the head and the foot portions of said elevator casing, in which path downwardly moving buckets are inverted, said buckets when moving upwardly opening upwardly and toward the outside of their path, partitioning in said buckets to provide in each bucket at least three side by side compartments for carrying contact material, a contact material feed chute connecting into the lower section of said elevator casing on that side nearest adjacent the upwardly moving, outwardly opening buckets, partitioning within said feed chute adapted to divide it into as many separate feed lines as there are compartments in each bucket, said partitioning being flared at the discharge end of said chute in such a manner as to divert the contact material discharged from each lane away from contact material discharged from any adjacent lane and into the bucket compartment corresponding to that lane, a discharge chute connected into said elevator casing near its upper end on the opposite side from said feed chute, partitioning in said discharge chute dividing it into as many discharge lanes as there are compartments in each bucket, said partition-

ing in said buckets being flared near the bucket opening in such a manner as to divert contact material being discharged from each compartment in each bucket away from that discharged from any other compartment and into the discharge lane corresponding to that compartment, passage defining means for flow of used contact material from the bottom of said conversion chamber into certain of said feed lanes in said feed chute, passage defining means for flow of regenerated contact material from the bottom of said regeneration chamber to the remainder of said feed lanes in said feed chute, means to withdraw used contact material from certain of said lanes in said discharge chute and means to pass said used contact material to said regeneration chamber, means to withdraw regenerated contact material from the remainder of said lanes in said discharge chute and means to pass said regenerated contact material to said conversion chamber.

2. In an apparatus for conversion of fluid hydrocarbons in the presence of a moving contact material the apparatus which comprises in combination, means defining a conversion chamber adapted to confine a contact material, means to admit a reactant thereinto, means defining a separate contact material regeneration chamber, a substantially vertical elevator casing having a head portion and a foot portion, an endless series of articulated buckets in said casing, means to support said buckets and to move them in a closed path forming a loop in both the head and the foot portions of said elevator casing, in which path downwardly moving buckets are inverted, said buckets when moving upwardly opening upwardly and toward the outside of their path, partitioning in said buckets to provide in each bucket at least three side by side compartments for carrying contact material, a contact material feed chute connecting into the lower section of said elevator casing on that side nearest adjacent the upwardly moving outwardly opening buckets, partitioning within said feed chute adapted to divide it into as many separate feed lanes as there are compartments in each bucket, said partitioning being formed and positioned to direct the contact material discharged from each lane separate from contact material discharged from any adjacent lane and into the bucket compartment corresponding to that lane, a discharge chute connected into said elevator casing near its upper end on the opposite side from said feed chute, partitioning in said discharge chute dividing it into as many discharge lanes as there are compartments in each bucket, said partitioning in said buckets being flared near the bucket opening in such a manner as to direct contact material being discharged from each compartment in each bucket away from that discharged from any other compartment and into the discharge lane corresponding to that compartment, passage defining means for flow of used contact material from the bottom of said conversion chamber into certain of said feed lanes in said feed chute, passage defining means for flow of regenerated contact material from the bottom of said regeneration chamber to the remainder of said feed lanes in said feed chute, means to withdraw used contact material from certain of said lanes in said discharge chute and means to pass said used contact material to said regeneration chamber, means to withdraw regenerated contact material from the remainder of said lanes in said discharge chute, and means to pass said

regenerated contact material to said conversion chamber.

3. In an apparatus for conversion of fluid hydrocarbons in the presence of a moving contact material the apparatus which comprises in combination, means defining a conversion chamber adapted to confine a contact material, means to admit a reactant thereto, means defining a separate contact material regeneration chamber, a substantially vertical elevator casing having a head portion and a foot portion, an endless series of articulated buckets in said casing, means to support said buckets and to move them in a closed path forming a loop in both the head and the foot portions of said elevator casing, in which path downwardly moving buckets are inverted, said buckets when moving upwardly opening upwardly and toward the outside of their path, partitioning in said buckets to provide in each bucket at least three side by side compartments for carrying contact material, a contact material feed chute connecting into the lower section of said elevator casing on that side nearest adjacent the upwardly moving, outwardly opening buckets, partitioning within said feed chute adapted to divide it into as many separate feed lanes as there are compartments in each bucket, said partitioning being flared at the discharge end of said chute in such a manner as to divert the contact material discharged from each lane away from contact material discharged from any adjacent lane and into the bucket compartment corresponding to that lane, a discharge chute connected into said elevator casing near its upper end on the opposite side from said feed chute, partitioning in said discharge chute dividing it into as many discharge lanes as there are compartments in each bucket, said partitioning in said buckets being formed near the bucket opening in such a manner as to direct contact material being discharged from each compartment in each bucket along a path separate from that discharged from any other compartment and into the discharge lane corresponding to

that compartment, passage defining means for flow of used contact material from the bottom of said conversion chamber into certain of said feed lanes in said feed chute, passage defining means for flow of regenerated contact material from the bottom of said regeneration chamber to the remainder of said feed lanes in said feed chute, means to withdraw used contact material from certain of said lanes in said discharge chute and means to pass said used contact material to said regeneration chamber, means to withdraw regenerated contact material from the remainder of said lanes in said discharge chute, and means to pass said regenerated contact material to said conversion chamber.

STANLEY M. MERCIER.
